Primary Examiner — Ian Simmons*Assistant Examiner* — Keith Frank(74) *Attorney, Agent, or Firm* — Banner & Witcoff, Ltd.**CLAIM**

The ornamental design for a bottle, substantially as shown and described.

DESCRIPTION

FIG. 1 is a front elevational view of the bottle showing my new design;

FIG. 2 is a right side elevational view thereof, the left side elevational view being a mirror image thereof;

FIG. 3 is a rear elevational view thereof;

FIG. 4 is a top plan view thereof with opposing sidewall details omitted for clarity purposes;

FIG. 5 is a bottom plan view thereof with opposing sidewall details omitted for clarity purposes; and,

FIG. 6 is a front bottom perspective view thereof.

The broken lines in the drawings illustrate the portions of the bottle that form no part of the claimed design.
